UNITED STATES PATENT OFFICE.

FRANK A. LISI, OF PHILADELPHIA, PENNSYLVANIA.

COMBINED BRUSH AND POLISHER.

Application filed May 29, 1926. Serial No. 112,568.

My invention relates to a combined brush head and polisher, for use in treating shoes or the like.

In accordance with my invention I combine a polishing cloth with a brush, whereby shoes or the like may be brushed and subsequently polished by the same implement. The polishing strip or cloth is secured to the ends of the brush head in a secure manner which will permit of one or both ends of the polishing strip or cloth being detached. When the polishing strip or cloth is used as such, it is passed over the face of the bristles, and secured to the brush head. My attaching means is extremely simple and may be used in connection with any number of polishing cloths, as they are substituted during the use of the brush.

In the accompanying drawings, forming a part of this specification, and in which like numerals are employed to designate like parts throughout the same,

Figure 1 is a side elevation of a combined brush and polisher embodying my invention, showing the polishing strip arranged upon the top of the brush head.

Figure 2 is a similar view, showing the polishing strip arranged on the face of the bristles,

Figure 3 is a plan view of the device, as shown in Figure 2,

Figure 4 is a plan view of the polishing strip or cloth,

Figure 5 is a similar view with the hem shown in section,

Figure 6 is a longitudinal section taken on line 6—6 of Figure 4,

Figure 7 is an enlarged central vertical longitudinal section through one end of the device, and

Figure 8 is a similar view showing a slight modification.

In the drawings, wherein for the purpose of illustration, is shown a preferred embodiment of my invention, the numeral 10 designates a brush as a whole, embodying a brush head or back 11, preferably having its ends 12 straight. This brush head carries bristles 13.

The numeral 14 designates a flexible polishing strip or cloth preferably formed of flannel, providing a face covered with fuzz 15. The ends of the strip 14 are folded back upon themselves, and stitched transversely, at 16 to provide hems 17.

The numeral 18 designates attaching

strips, preferably formed of resilient material, such as spring metal, although other material may be employed, such as celluloid, fiber or the like. These strips are adapted for insertion within the hems 17, and are held therein by frictional engagement, or by other means, if desired. Each strip is provided with any suitable number of openings, one of which is indicated by the numeral 19. These openings are adapted to register with openings 20, formed in the opposite sides of the hem. The strips 18 are provided with radial slits 21, arranged in an annular group surrounding the openings 19. These slits render the wall of the opening resilient.

Secured to the edges of the ends 12, are headed studs 22, having head 23, which are preferably larger than the openings 19, while the shanks of these studs are smaller in diameter than the openings 19. It is thus seen that the openings 19, by virtue of the slits 21, constitute resilient sockets, which may be forced over the heads of the studs and will then be securely held upon the studs, in a detachable manner. By this means, both ends of the polishing strip are detachably secured to the brush head, but it is to be understood that one end of the strip may be permanently secured to the brush head, if desired.

In Figure 8, I have shown a modification of the invention, in which the strip 18 is provided with an opening 24, which is larger than the head 23 of the stud. The slits 21 are omitted. The head of the stud may, therefore, be inserted through these openings and the tension of the strip 14 will prevent the attaching strip 18 from being accidentally separated from the stud.

From the foregoing description, it will be seen that the polishing strip 14 may be held upon the top of the brush head 11, as indicated in Figure 1, so that the bristles 13 may be employed in the usual brushing action. One end of the polishing strip 14 may now be detached from the brush head and the strip passed over the face of the bristles 13, and the free end of the strip again attached to the corresponding end of the brush head. The cloth may then be employed as a polishing medium. In the use of the device, the brush will outlast a number of polishing cloths and it will become necessary to substitute new polishing cloths. When this is done, the attaching strips 18 may be removed

from within the hems and inserted into the hems of the new polishing cloths. It is thus seen that the attaching means are not discarded with the old polishing cloth. This will materially reduce the cost encountered in the use of the device.

It is to be understood that the form of my invention, herewith shown and described is to be taken as a preferred example of the same, and that various changes in the shape, size and arrangement of parts may be resorted to without departing from the spirit of my invention, or the scope of subjoined claims.

Having thus described my invention, I claim:-

1. The combination with a block, of a polishing strip to be used in connection therewith, provided at its ends with transverse hems, headed studs attached to the ends of the block and arranged adjacent to the central longitudinal axis of the same, and transverse stiffening attaching ribs arranged within the transverse hems, said ribs being

provided at points substantially equi-distantly spaced from the ends thereof with openings adapted for the reception of the headed studs, the headed studs and stiffening ribs holding the polishing strip substantially flat upon the block.

2. The combination with a block, a polishing strip to be used in connection therewith, provided at its ends with transverse hems, substantially flat metallic attaching strips inserted within the transverse hems, said metallic strips being provided at points substantially equi-distantly spaced from the ends thereof with openings, the walls of the openings being radially slit to provide resilient sockets, and headed studs attached to the ends of the block adjacent to the central longitudinal axis of the same, the studs and strips serving to hold the polishing strip substantially flat upon said block.

In testimony whereof I affix my signature.

FRANK A. LISI.
